UNITED STATES PATENT OFFICE.

GEORGE P. TILTON, OF NEWBURYPORT, MASSACHUSETTS, ASSIGNOR TO
THE TOWLE MANUFACTURING COMPANY, OF SAME PLACE.

DESIGN FOR A SPOON.

SPECIFICATION forming part of Design No. 24,528, dated August 6, 1895.

Application filed June 18, 1895. Serial No. 553,233. Term of patent 7 years.

To all whom it may concern:

Be it known that I, GEORGE P. TILTON, of Newburyport, in the county of Essex and State of Massachusetts, have invented and produced a new and original Design for Spoons, of which the following is a full, clear, and exact description.

Reference is to be had to the accompanying drawings, forming a part of this specification, in which—

Figure 1 represents the obverse of a spoon embodying my design; Fig. 2, the reverse, and Fig. 3 a cross-section on line 33 of Fig. 1.

The leading feature of my design consists in the bowl divided into a plurality of surfaces ranging lengthwise of the bowl and in planes at an angle to each other.

In the drawings, A is the bowl and B the handle, which may have any suitable configuration or ornamentation. The surfaces $a a' a''$ of the bowl, as will appear best from Fig. 3, are in planes at an angle to each other, and, as will be seen from Figs. 1 and 2, the said surfaces follow the longitudinal curves of the bowl and are narrow both at the point and inner end of the bowl.

I claim—

The design for a spoon herein shown and described.

GEORGE P. TILTON.
